UNITED STATES PATENT OFFICE.

JOHN ROGERS FLANNERY AND ETHAN I. DODDS, OF PITTSBURGH, PENNSYLVANIA,
ASSIGNORS TO FLANNERY BOLT COMPANY, OF PITTSBURGH, PENNSYLVANIA.

STAYBOLT STRUCTURE.

1,346,645.

Specification of Letters Patent. Patented July 13, 1920.

Application filed September 10, 1919. Serial No. 322,873.

To all whom it may concern:

Be it known that we, JOHN ROGERS FLANNERY and ETHAN I. DODDS, citizens of the United States, and residents of Pittsburgh, 5 in the county of Allegheny and State of Pennsylvania, have invented certain new and useful Improvements in Staybolt Structures; and we do hereby declare the following to be a full, clear, and exact description 10 of the invention, such as will enable others skilled in the art to which it appertains to make and use the same.

This invention relates to improvements in staybolt structures for boilers, and more 15 particularly to that type in which the head of the staybolt is seated in an opening in the boiler sheet and inclosed by a cap or closure,—one object of the present invention being to provide, in such a staybolt structure, a yielding cap or closure which shall surround the bolt opening in the boiler sheet and inclose the projecting portion of the head of a staybolt having a tell-tale hole which extends from the inner end of the 20 bolt and terminates within the head thereof, said flexible cap or closure being welded to the outer boiler sheet and having a part which lies over and in contact with the head of the bolt so that said cap or closure will normally tend to retain the staybolt head on its seat but permit longitudinal play of the staybolt.

With this and other objects in view, the invention consists in certain novel features 35 of construction and combinations of parts as hereinafter set forth and pointed out in the claims.

The accompanying drawing is a sectional view, partly in elevation, showing an embodiment of our invention.

1 represents an outer boiler sheet and 2 the inner sheet of a boiler.

The outer boiler sheet is provided with an opening 3, a portion of the wall of which 45 has a general tapering shape and formed with a transversely curved or rounded seat 4 for the rounded head 5 at the outer end of a staybolt 6. The inner end of the staybolt may be threaded as at 7 and passed 50 through a hole in the inner boiler sheet 2 and the inner end of the bolt may be upset as at 8.

The rounded head 5 of the staybolt projects outwardly beyond the plane of the

outer face of the outer boiler sheet 1 and is 55 inclosed by a cap or closure 9 which surrounds but is spaced from the opening in boiler sheet 1.

The cap or closure is made of spring metal with a peripheral wall 10 which may be 60 seated on the boiler sheet and be disposed at approximately right angles thereto, and the spring or yielding cap or closure is made with a depressed part 11 having a central curved portion 12 which overlies and 65 engages the outer end of the bolt head so that when the cap or closure is secured to the boiler sheet, it will tend normally to press the bolt head against its seat and permit longitudinal play of the bolt.

The cap or closure 9 is permanently united 70 to the outer boiler sheet by a weld 13 surrounding the edge of the wall 10 of said cap or closure.

It will be observed that the cap or closure 75 9 permanently incloses the bolt head and is permanently secured to the boiler sheet around the opening therein, and it is desirable, for testing purposes, that the bolt be provided with a tell-tale hole which shall 80 be accessible from the inner end thereof. We therefore provide the staybolt with a tell-tale hole 14 which extends from the inner end of the bolt and terminates at its outer end in the bolt head. 85

Having fully described our invention, what we claim as new and desire to secure by Letters-Patent, is:—

1. In a staybolt structure, the combination with a boiler sheet having an opening, 90 and a staybolt having a head mounted in said opening, of a spring cap or closure secured to the boiler sheet and extending over and inclosing the bolt head, said cap or closure having a central part bearing on said 95 bolt head.

2. In a staybolt structure, the combination with a boiler sheet having an opening, and a staybolt having a head mounted in said opening, of a spring cap or closure welded 100 to the boiler sheet around the opening therein and having a depressed part over and bearing on the head of the staybolt.

3. In a staybolt structure, the combination with a boiler sheet having an opening, 105 of a staybolt having a head mounted in said opening said staybolt having a tell-tale hole extending from its inner end and terminat-

ing within the headed outer end of said bolt, a spring cap surrounding the opening in the boiler sheet and welded to the latter, said spring cap having a central depressed part
5 provided with a portion bearing on the head of the staybolt.

In testimony whereof we have signed this

specification in the presence of two sub-
scribing witnesses.

JOHN ROGERS FLANNERY.

ETHAN I. DODDS.
